Inventor:
Antoni J. Kolanko,
By Joseph R. Ross
his Attorney.

UNITED STATES PATENT OFFICE.

ANTONI J. KOLANKO, OF CHICAGO, ILLINOIS.

COLLAPSIBLE LIFE-BOAT.

1,076 291.

Specification of Letters Patent.

Patented Oct. 21, 1913.

Application filed March 17, 1913. Serial No. 754,833.

To all whom it may concern:

Be it known that I, ANTONI J. KOLANKO, a citizen of the United States, and a resident of the city of Chicago, county of Cook, and State of Illinois, have invented certain new and useful Improvements in Collapsible Life-Boats, of which the following is a specification.

My invention relates to boats and more specifically to that class thereof designed for use especially as life boats.

The object of my invention is the production of a boat as mentioned which will be of a collapsible nature so that, when not in use, the same may be folded into compact form for storage in a limited space.

A further object is the production of a boat as mentioned which may be readily and expeditiously folded or unfolded, and which when in unfolded or distended condition will be adapted to effectually serve the purpose for which the same is intended.

Other objects will appear hereinafter.

With these objects in view my invention consists in the combinations and arrangements of parts hereinafter described and claimed.

The invention will be best understood by reference to the accompanying drawing forming a part of this specification, and in which, Figure 1 is a perspective view of a boat embodying my invention, the same being shown in distended condition, Fig. 2 is a central section of the boat in collapsed or folded condition, illustrated partially diagrammatically, Fig. 3 is an enlarged horizontal section through one of the pivots which connect the ribs of the foldable frame of the boat, and Fig. 4 is a slightly enlarged detail section.

The preferred form of construction as illustrated in the drawing comprises a foldable frame consisting of a plurality of substantially U-shaped metallic ribs 1, 2, 3, 4 and 5, said ribs being pivotally connected at their ends by pivot pins 6 so as to permit of said ribs being swung freely as will be readily understood. Said ribs are of graduated size, so as to permit of the same being folded together in coplanar relation, as clearly shown in Fig. 2.

To the frame thus formed is secured the collapsible body 7 of the boat which is formed preferably of a suitable, durable water-proof cloth or fabric, the same being suitably secured as by cement to the bight

portions of said ribs. The arrangement is such, as will be observed, that, when the frame of the boat is unfolded, as shown in Fig. 1, the body 7 will be drawn taut by the frame ribs to form a concave body which is adapted to effectually serve as a life boat. In order to prevent capsizing the bight or outer portions of the ribs 3, 4, and 5 which are positioned at the under side of the boat, when in operative condition, are of increased thickness, the increasing of the thickness of said ribs at these points providing ballast, as will be readily understood.

In order to releasably lock the frame of the boat in unfolded condition, housings 8 are provided which are secured to the outer sides of the extended ends of the rib 1. Slidably mounted in each of the housings 8 is a spring pressed latch 9 the inner end of which passes through an opening 10 formed in the corresponding end of the rib 1, the beveled inner ends of the latches 9 being adapted to engage corresponding slots 11 provided in the ends of the rib 2 when the latter is arranged in alignment with the rib 1, as shown in the several views. The inner ends of the latches 9 being beveled or inclined as shown, in the unfolding of the boat, when the ribs 1 and 2 reach their operative positions said latches will automatically drop into engagement with the slots 11 and thus automatically lock the boat in operative position. Said latches are, however, provided with exteriorly projecting handles 12 through the medium of which the same may be moved outwardly in order to unlock the ribs to permit of folding of the boat together.

In order to permit of ready folding of the body 7 when the frame ribs are swung together, as shown in Fig. 2, it has been found that said body must be loosened at the pivotal points of the frame to permit of the drawing of the body slightly downwardly or toward the bights of said ribs. With this in view, the body 7 adjacent the pivots of the frame is not secured to the ribs, ball-and-socket fastenings being provided for releasably securing said body at the pivotal points. The socket members 13 are fastened to the body at the pivotal points, said socket members being adapted to releasably engage balls 14 which are formed at the outer ends of the pivot pins 6.

In order to facilitate folding or unfolding

of the ribs of the frame, handles 15 are provided at the outer sides of the bight portions of the ribs 1, 2, 3 and 4. With this provision it will be seen, that the manual folding or 5 unfolding of the boat may be effected with ease and expedition.

A life boat of the construction set forth is durable and economical in construction, the same may be readily and expeditiously unfolded for use, and when not in use the same 10 may as readily and easily be folded together for storage; the same is adapted to ride smoothly in the water and in use will be found adapted to effectually serve the purpose for which the same is intended.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 25 the appended claims.

Having described my invention what I claim as new and desire to secure by Letters Patent is:

- 30 1. A boat comprising a collapsible body; a plurality of pivotally connected substantially U-shaped ribs for holding said body in distended condition; and means for releasably locking said ribs in operative position, said ribs, when released, being adapted to be folded into coplanar position, substantially as described.
- 35 2. A boat comprising a collapsible body; a plurality of pivotally connected substantially U-shaped ribs for holding said body in distended condition; and means for releasably locking said ribs in operative position, 40 said ribs, when released, being adapted to be folded into coplanar position, substantially as described.

tion, said ribs being of graduated sizes so that, when released, the same may be folded in coplanar positions with said ribs positioned one within the other, substantially as 45 described.

3. A boat comprising a collapsible body; a plurality of substantially U-shaped ribs having their ends pivotally connected, said body being secured to the bights of said 50 ribs; and a spring pressed latch co-operating with the adjacent ends of the endmost of said ribs for releasably locking the latter in operative position, substantially as described.

4. A boat comprising a collapsible body; a plurality of pivotally connected substantially U-shaped ribs for holding said body in distended condition; and means for releasably locking said ribs in operative position, 60 said ribs, when released, being adapted to be folded into coplanar position, said body being releasably connected to said ribs at said pivotal points, substantially as described.

5. A boat comprising a collapsible body; a plurality of pivotally connected substantially U-shaped ribs for holding said body in distended condition; means for releasably locking said ribs in operative position, said 70 ribs, when released, being adapted to be folded into coplanar position; and ball-and-socket clasps releasably connecting said body to said ribs at said pivotal points, substantially as described.

In testimony whereof I have signed my name to this specification in the presence of two subscribing witnesses.

ANTONI J. KOLANKO.
